UNITED STATES PATENT OFFICE.

ABRAHAM SUSSELES, OF BROOKLYN, NEW YORK.

DESIGN FOR A BELT.

Application filed December 4, 1925. Serial No. 15,637. Term of patent 3½ years.

To all whom it may concern:

Be it known that I, ABRAHAM SUSSELES, a citizen of the United States of America, residing at 3090 Bedford Avenue, in the borough of Brooklyn, county of Kings, city and State of New York, have invented a new, original, and ornamental Design for a Belt, of which the following is a specification, reference being had to the accompanying drawing, forming part thereof.

In the drawing the figure is a perspective of a belt embodying my design, and the design as shown is repeated continuously around said belt.

I claim:

The ornamental design for a belt as shown. Signed at New York city, county of New York, State of New York, this 27th day of November, 1925.

ABRAHAM SUSSELES.
